UNITED STATES PATENT OFFICE.

LINDEN A. THATCHER, OF BELLEVILLE, NEW JERSEY, ASSIGNOR TO UNDERWOOD ELLIOTT FISHER COMPANY, OF NEW YORK, N. Y., A CORPORATION OF DELAWARE.

STENCILING MACHINE.

Application filed May 18, 1926. Serial No. 109,833.

This invention relates to stencil-printing duplicating machines, and more particularly to improvements in the well-known Underwood revolving duplicator as shown and described in the pending application of Edward G. Rowley, filed June 24, 1924, Serial No. 721,982, now Patent No. 1,618,309, dated Feb. 22, 1927.

In the present Underwood revolving duplicating machines, the sheets that are to receive a stencil impression are fed manually to a position where the leading-in edge of a sheet enters between the stenciling cylinder and a co-operating platen-roller, and by a single revolution of the stencil-carrying cylinder the sheet is picked up and fed mechanically to the delivery side of the machine. A machine of this nature requires correct timing between the entrance position of the leading-in edge of the sheet and the initial stenciling line on the cylinder, and hence every revolution of the cylinder in a stenciling direction should be arrested at a fixed stop position, which position also becomes the initial starting position of the next following sheet. This cylinder stop includes a pallet having a pair of stop elements, one of which operates to arrest the cylinder at the end of a stenciling operation, and the other stop automatically shifts to become a back-stop to prevent a reverse rotation of the cylinder, in the manner disclosed in the patent to James E. Shaver, Jr., No. 1,583,803, dated May 11, 1926.

The usual duplicating machine provides a table with a side-edge guide to receive a pile of work-sheets at the introductory side of the cylinder and the operator slides the top-most sheet into the feeding position of the cylinder. This mode of operation promotes irregular stenciling execution, due sometimes to a delay in the cylinder picking up a sheet or sometimes causing a cornerwise entrance of a sheet, and hence a positive registration between the stencil and work-sheet, so essential for neatness and effect, cannot be maintained due to the imperfect control of the sheet. If the gripping of the sheet by the cylinder is delayed or the cylinder is accidentally rotated on a stenciling direction without a work-sheet insertion, the inked stenciling element is brought into contact with an underlying platen-roller, which roller will then transfer any ink thereon to the underface of the next succeeding work-sheet,

which is a source of annoyance to the operator.

One feature of the present invention provides means that are operative automatically to prevent any possibility of the inked stenciling element being rotated into contact with the platen-roller, except by a deliberate abuse of a stop control element. To this end, the leading-in edge of the inked stencil on the cylinder is normally separated from the position of the platen-roller by an inactive cylinder-surface gap of predetermined extent to enable the cylinder to have a free initial rotary movement before the stencil is brought into stenciling co-operation with the platen-roller, which free rotary movement of the cylinder is arrested by a stop-member controlled by the work-sheet. This arrangement provides that, while the cylinder is locked against rotation in one direction, it may be rotated in a reverse direction only a limited distance that is insufficient to bring the inked stencil into contact with the platen-roller.

This inactive gap in the surface of the cylinder between the stenciling element and the platen-roller may also be employed for a novel method of delivering work-sheets to the cylinder. Instead of manually feeding a work-sheet to pass between the cylinder and the platen-roller, which promotes uncertain results, supplemental feeding means are provided to mechanically feed a work-sheet between the cylinder and platen-roller. The surface travel of the supplemental feed-rolls may be equal to the surface travel of the cylinder and platen-roller, and hence the travel of the work-sheet towards the cylinder will synchronize with the rotary surface travel of the cylinder, and the work-sheet will be picked up without any distortion or displacement thereof. When the proper control of the work-sheet by the cylinder is assured, the supplemental feed is rendered inactive, and the cylinder and platen-roller complete the work-sheet feeding operation.

To time the entrance of the work-sheet to the initial stenciling position, stop-pins are positioned to pass through the introductory table of the machine a predetermined distance from the gripping position of the platen-roller and just inside the supplemental feed-rolls. These feed-rolls are normally separated, so that the work-sheet may be freely-introduced therebetween with the

leading-in edge engaging said stop-pins. The initial rotation of the cylinder from its normal stop position closes the supplemental feed-rolls to feed, and simultaneously withdraws the stop-pins to permit the advancement of the work-sheet to the stenciling position. These feed-rolls, in becoming effective to feed after said sheet has been manually advanced between said rolls and against the stop-pins, provide a mechanical control of the sheet until the stenciling cylinder and the platen-roller jointly become sheet-feeding elements during the stenciling operation.

In some prior machines, the platen-roller is normally out of engagement with the stenciling cylinder and the introduction of a work-sheet to the machine requires mechanism that automatically raises the roller for a co-operative movement between the cylinder and the stenciling element. Such machines require a positive train of gears to transmit motion from the rotating cylinder to the co-operative platen-raising parts, which results in a noisy operation and an expensive and complicated structure to manufacture and maintain. In the present invention the platen-roller, during a stenciling period, is constantly in spring-pressed rolling engagement with the face of the cylinder or the face of the work-sheet, and the power derived from this frictional surface engagement of the platen-roller is transmitted to drive a series of feed-rolls, and requires no complicated timing devices, except that said driven feed-rolls have a diameter similar to the diameter of the platen-roller. said rolls and the platen-roller having a constant rotary movement during the entire rotation of the cylinder. The timing elements include a cam adjustably fixed to the cylinder and a coacting trip on the frame operable to vibrate companion feed-rolls into feeding relation with the cylinder-driven feed-rolls for an operative feeding period necessary to carry a work-sheet to the platen-roller and then release the work-sheet, the extent of this intermittent or feed-stopping motion of the companion feed-rolls being predetermined automatically by said cam.

Another feature includes a cylinder stop-pawl on the frame that is normally in the path of a part secured to the cylinder and operable by the cam-actuated trip to swing clear of said part if a sheet-feeding movement accompanies the rotation of the cylinder, but, if the cylinder is rotated without the insertion of the work-sheet, said pawl is automatically released to intercept the rotating cylinder before the leading edge of the inked stencil can reach the platen-roller and soil the face thereof with ink. To this end, when the stop-pins are withdrawn by the action of the cylinder-cam to permit the passage of the work-sheet to the platen-roller, the action of the cam releases the trip to re-

store the stop-pins, but these pins, instead of being restored, engage with the under face of the work-sheet, and, by thus cutting off a portion of the pin-restoring movement, the stop-pawl, that otherwise would check the rotation of the cylinder, is held in an ineffective position to permit the cylinder to have an uninterrupted rotary movement of a full revolution for a stenciling operation. In this manner the stop-pins perform a double function, one function for leading in stops for the inserted work-sheet, and another function for controlling the movement of the cylinder stop-pawl through the premature arrest of the released stop-pins by the work-sheet after said work-sheet has passed into feeding position between the rotating cylinder and its co-operative platen-roller.

Another feature includes a cam-actuated connection to the vibratory feed-rolls that is flexible in its character, so that said feed-rolls will automatically render themselves operable to positively feed a thin work-sheet or a thicker postal-card. It is obvious that such a flexible connection, which, in the present case, is a compression spring, may also include adjustable features to increase or decrease the pressure required to positively control a work-sheet until the cylinder and the platen-roller have assumed feeding control of said sheet.

Another important feature includes the manner of applying these new features to a standard Underwood product with very little if any change in the standard machine.

Other features and advantages will hereinafter appear.

In the accompanying drawings,

Figure 1 is a side elevation of the Underwood duplicating machine, showing the present invention operatively attached thereto and with portions of the frame broken away.

Figure 2 is a reduced top plan view to diagrammatically illustrate the relative positions of the lower paper-feeding rolls, paper stop-pins, platen-roller and the side guide to a work-sheet.

Figure 3 is a top plan view of the machine with the stenciling cylinder and the paper-table removed.

Figure 4 is a skeleton side view of the operative parts moved from the normal inoperative positions of Figure 1 to operative positions where the work-sheet has been advanced to the stenciling position, the cylinder stop shifted to an inoperative position, and the stencil about to engage with the work-sheet.

Figure 5 shows the parts of Figure 4 further advanced in a stenciling direction where the feeding control of the work-sheet has passed to the control of the platen-roller, the supplemental rolls rendered inoperative to feed, and the cylinder stop held in an inoperative position through the abutment of the

work-sheet leading-in paper-stop against the under face of the work-sheet.

Figure 6 shows the cylinder advanced without a previously-inserted work-sheet and the leading-in stop-pins having nothing to check their return movement, the cylinder locking pawl having been restored to check the rotation of the cylinder before the inked stencil can engage the face of the platen-roller to soil it with ink.

Figure 7 is a detail view of the cylinder-operating handle and its carrier, showing the manner of adjusting the carrier to the cylinder to vary the normal position of the stencil-ing element to the stenciling position.

The frame of the machine includes two upright side frames 10 and 11 joined together at the base by front and rear cross-bars 12 and 13, respectively, and provided with four rubber cushion feet 14. The side frame 11 terminates at a hub 15 provided with a stud 16 projecting inwardly to provide a bearing for a rotatable cylinder 17 that includes a webbed head 18 at one end that takes a center bearing upon the stud 16, and an open annular head 19 at the opposite end formed with a peripheral track 20 that rides upon three anti-friction rolls 21 carried on the side frame 10, said rolls being disposed so that the weight of this end of the cylinder will be carried by the lower center roll 21 and the cylinder held in aligned position by the two upper rolls 21 secured to extension-arms of the frame-end 10. The two cylinder-heads 18 and 19 are conditioned to be joined by a sheet-metal cylindrical section 22 formed with perforations in a conventional manner to supply ink to a fabric covering on the outer face of the cylinder. The cylinder as a unit may be withdrawn from the machine by the manual release of suitable cylinder-retaining means secured to the frame-end 10, similar to that shown in the aforesaid Rowley application.

In the present invention the supply side of the machine is at the left side of Figure 1, and the cylinder is rotatable in a counter-clockwise direction to carry the work-sheet to the delivery side at the rear of the machine. Manual cylinder-rotating means includes a handle 23, secured to a carrier 24 slidably mounted on the side of the annular head 19 held in position by a band 24^a encircling said head with the ends thereof secured to said carrier, and clamp-screws 25 to clamp the carrier at any position along said head predetermined by the character of the work-sheet. Means to arrest the cylinder at the end of each revolution thereof includes two stop-lugs 26 and 27 forming a part of the carrier 24 and a co-operating pallet 28 that includes two stop-arms 31 and 32 normally spring-pressed against a stop-pin 29 by a spring 30. During the stenciling rotation of the cylinder the lug 27 engages and cams the

stop-arm 31 outwardly to vibrate the stop-arm 32 inwardly into the path of the advancing lug 26 to arrest the cylinder. The stop-arm 32 will hold its engagement with the face of the lug 26 until the pressure is removed from the handle 23, when the spring 30 will restore the pallet 28 to its normal position against the pin 29, and the stop-arm 31 thereof will shift to the position of Figure 1 to intercept the lug 27 against the reverse rotation of the cylinder. It is obvious under these conditions that the cylinder is locked against rotation in a clockwise direction, but there is nothing to prevent the cylinder from having a counterclockwise rotation, and nothing to prevent the inked stenciling element, when rotated without a work-sheet, from soiling the face of the platen-roller 33. If, however, it is desirable at any time to rotate the cylinder in a clockwise direction, a finger-piece 28^a is provided to lift the arm 32 and withdraw the stop-arm 31 from the path of the stop-lug 27.

The platen-roller 33 is positioned directly under the axis of the cylinder 17 and preferably during a stenciling period is always in rolling contact therewith throughout its length. This roller 33 may have a soft pliable body carried by a shaft 34 projecting through each end of the roller to take roller bearings within the free end of an arm 35 at each end of the roller, which arms are mounted upon a stationary rod 36 and held against displacement thereon between bosses on the frame and collars on the rod. In thus providing that each arm 35 shall have independent swinging movement upon the rod 36, the platen-roller becomes self-adjusting to the face of the cylinder under a suitable spring-tension, presently to appear.

It will be noted that the bearings in the arms 35 for the ends of the shaft 34 are open at the top, so that the platen-roller 33 may be readily removed for cleaning or other purposes.

37 is a rod connecting the two arms 35, and at the center thereof is a link 38 connecting below with a crank-arm 39 fixed on a rock-shaft 40 taking bearings within ears 41 depending from the lower edge of each side frame 10 and 11. This shaft 40 may be rocked by a lever 42 secured to the shaft outside the frame and including a finger-piece 43 and a tongue 44. A latch 45 pivotally hung upon a screw 46 engages the tongue 44 on said lever 42 when the latter is depressed, as shown at Figure 1, and may be formed with a key 47 to withdraw the latch 45 to release the lever 42 to the action of a restoring spring 48^a tensioned between an ear on the latch and an ear on the lever. The depression of the lever 42 to its locked position (Figure 1) rocks the shaft 40, the crank-arm 39, the two arms 35 and the platen-roller 33 into pressing engagement with the cylinder 130

17, and, after a stenciling period, this pressure should be removed to avoid the formation of a flat spot on the roller 33, the key 47 operating, as described, to release and 5 lower said roller to an inoperative position. A description of the mechanism up to this point is practically the same as that disclosed in the afore-mentioned Rowley application.

The present invention includes the lengthening of one end of the platen-roller shaft 34 to receive a gear 48 secured thereto outside the adjoining arm 35. The platen-roller 33, through its surface engagement with the cylinder 17, becomes a driving element for 10 the gear 48 that is in toothed engagement with an idler gear 49, loosely mounted upon one end of the rod 37, to communicate the same rotary movement of the gear 48 to a gear 50 secured to the end of a shaft 51 having bearings in the two arms 35. It is desirable that both gears 48 and 50 have the same pitch diameter, so that the rotation of the roller 33 will synchronize with the rotation of the shaft 51, that carries a series of feed- 15 rolls 52 to provide a surface travel for said rolls that is equal to the surface travel of the roller 33.

The usual supply table 53 is formed with four perforations 54 to give clearance for 20 four feed-rolls 52 that operatively have their paper-feeding faces in alignment with the upper face of the table 53. The feed rolls include a flanged barrel-section 52^a to receive rubber rings seated therein, and a hub 55 that 25 may be secured to the shaft 51 by suitable screws.

To render rolls 52 operative to feed a work-sheet, companion pressure-rolls 56 rotate upon a rod 57 in alignment with the rolls 52 30 and are swingable into and out of engagement therewith. This swinging movement is induced by securing the ends of the rod 57 to the ends of two arms 58 and 59 positioned adjacent the inside walls of the two frames 10 35 and 11 and secured to a rock-shaft 60 underlying the supply table 53, and having bearings at each end in the side frames, the arm 59 having an extension 61 that terminates at a perforated ear 62, bent at right angles to said extension. A push-rod 63 passes 40 through a perforation in the ear 62, and the end thereof may be threaded to receive two check-nuts 64 to bear against one face of the ear 62, while a spring 65 may be adjusted 45 around the rod and compressed between said ear and a collar 66 on said rod. The rod 63 extends rearwardly, where the free end is secured to an arm 67, secured to a rock-shaft 68 extending across the machine and having end 50 bearings in the two frames 10 and 11. The shaft 68 projects through said frame 10, and the free end carries an arm 69 provided with a roller 70 at its free end.

The description up to this point provides 55 that, when the arm 69 is vibrated by means

acting upon the roller 70, the shaft 68 is rocked to convey motion to the arm 67, to push the rod 63 forwardly to vibrate the extension 61, rock the shaft 60, and swing the four rolls 56 into engagement with the four 70 rolls 52, the pressure between the rolls 56 and 52 depending upon the pressure derived from the compressed spring 65.

To actuate the roller 70 and control the movement of the pressure-rolls 56, a cam-plate 71 may form a part of the carrier 24 and be formed with a cam-face 72 and a dwell-face 73. The roller 70, riding over the cam-face 72, brings the rolls 56 and 52 into coaction, but the rod 63 continues to move forwardly, and, by the time said roller 70 reaches the dwell-face 73, the spring 65 is compressed and the check-nuts 64 have been moved from their contact with the ear 62, as shown in Figure 4, giving the rolls 56 a flexibility predetermined by the compression of the spring, to compensate for varying thicknesses of work-sheets. To restore these several parts when the roller drops off the dwell 73, as shown at Figure 5, the arm 67 may be connected by a spring 67^a, secured to the frame, to rock the shaft 68 until checked by a stop-pin 69^a striking a lip 69^b in the arm 69. The feeding interval of the rolls 56 and 52 depends upon the length of the dwell 73, to carry the leading-in 95 edge of the work-sheet from a fixed initial position to pass to the control of the rotating cylinder and associated platen-roll, as will presently appear.

A rock-shaft 74 extends across the machine 100 between the two side frames 10 and 11, and carries two arms 75 positioned within said frames with their free ends extending forwardly to support a rod 76 connecting the two arms. This rod 76 may be provided with 105 a plurality of pins 77 rising vertically from the rod to enter guide-holes in a cross-bar 78, and then pass upwardly through clearance holes in the table 53, to project slightly above the table. These pins 77 operate as leading-in 110 stop-pins by arresting and aligning the leading-in edge of the work-sheet, and, to properly position the edge of the sheet to the pins 77, the usual shield-plate 79, secured to the two side frames 10 and 11 to shield the 115 operator's hands from the inked surface of the stencil, is slightly changed at the inner longitudinal edge to form a narrow paper-chute, through which the ends of the pins 77 project.

To control the movement of the stop-pins 77, a crank-arm 80 may be secured to the outer end of the rock-shaft 74 and formed with a short arm 81 to abut the lip 69^b of the arm 69, and has a link-connection 82 to one arm 83 of a bell-crank lever pivoted to the face of the frame 10 and formed with a cylinder stop-arm 84. A spring 85 tends to hold the arm 83, normally against a stop-pin 86, and, through the connections 82 and 80 to the 120

rock-shaft 74 and to the arms 75 secured thereto, holds the stop-pins 77 in the raised position of Figure 1, and the stop-arm 84 will lie in the path of a stop-pin 84^a projecting from the face of the cam-plate 71. It is desirable that the pressure of the stop-pins 77 against the under face of the work-sheet shall be as light as possible, and in this connection it will be noted that the several parts are arranged upon both sides of the rock-shaft 74, to counterbalance each other, and the parts, as a unit, are practically in equipoise, and hence require only the very light spring 85 to restore the stop-arm 84 at one side of the shaft 74, and the stop-pins 77 at the opposite side of said shaft.

At Figure 1, the machine is shown with the parts at normal positions for a stenciling operation with the lever 42 depressed and locked to lift the platen-roller 33 into feeding contact with the face of the cylinder 17. A work-sheet 87 may be laid upon the table 53, pushed forwardly between the open feed-rolls 52 and 56 to bring the leading-in edge thereof against the pins 77, and shifted sideways, so that one side edge will rest against a side guide 88. The handle 23 is pushed in a direction away from the operator to rotate the cylinder, the initial rotary movement thereof causing the roller 70 to ride over the inclined face 72 of the cam-plate 71 to rock the shaft 68. The rocking of this shaft 68 rocks the arm 67 forwardly to flex the spring 67^a, pushes the rod 63 to rock the shaft 60, vibrates the rolls 56 against the top face of the work-sheet, and renders the two series of feed-rolls 56 and 52 operative to feed said sheet under the pressure derived from the compressed spring 65. The rocking of the shaft 68 also vibrates the arm 69 to engage with the arm 81, which rocks the shaft 74, to draw the arms 75 downwardly to remove the pins 77 from the path of the leading-in edge of the work-sheet to be fed toward the platen-roller 33. Simultaneously, the rock-shaft 74 swings the arm 80 and the connection 82 upwardly to vibrate the bell-crank and remove the stop-arm 84 thereon from the path of the advancing stop-pin 84^a. During this initial movement of the cylinder 17, the platen-roller 33 and the feed-rolls 52 have been rotated ineffectively, and the leading edge 22^a of the stenciling element has been advanced toward the platen-roller. Further rotation of the cylinder causes the roller 70 to ride over the dwell-face 73 and the work-sheet is fed forward and between the face of the cylinder and the face of the platen-roller. The stop-pin 84^a has passed the locking position for the stop-arm 84, and the leading edge 22^a of the stencil is about to be rotated into contact with the top face of the work-sheet to begin a stenciling operation. The roller 70 now passes from the dwell 73 of the cam-plate 71, and, under the influence of the spring 67^a, the shaft 68 is rocked reversely, and, through the connections to the shaft 60, the vibratory feeding rolls 56 are raised to their normal inoperative position, as shown in Figure 5. While the feed-rolls 52 continue to rotate with the platen-roller 33, they are ineffective to feed the work-sheet, and the subsequent feeding operation is carried on by the platen-roller 33. During this initial feeding movement of the work-sheet, the stop-arm 84 is held out of the path of the stop-pin 84^a, and the related parts are so timed that the stop-pin 84^a passes the position of the stop-arm 84, and the pins 77 are brought into contact with the face of the work-sheet until the end of the sheet is reached, when they are fully restored and the stop-arm 84 is shifted to a position to intercept the stop-pin 84^a during the next rotation of the cylinder. The cylinder is rotated until the lug 27 cams the stop-arm 31 outwardly to vibrate the companion stop-arm 32 into the path of the advancing lug 26, which arrests the rotation of the cylinder, and, as soon as the pressure is removed from the handle 23, the spring 30 will withdraw the arm 32 and the arm 31 will pass to the rear of the lug 27, thus conditioning the cylinder for the next rotation in a stenciling direction, but checking a reverse rotation thereof by the arm 31 engaging with the lug 27.

The set relation of the parts shown in Figure 1 provides for an initial blank space at the head of the work-sheet, but this blank space for a heading may be increased by shifting the carrier 24 a greater distance from the leading edge 22^a of the inked stencil.

From this description it is obvious that if the cylinder 17 is rotated in a stenciling direction without first inserting a work-sheet, the roller 70 will be actuated by the cam 71, and the pins 77 and the stop-arm 84 will be withdrawn, but the roller 70 will drop from the dwell 73 to permit the stop-arm 84 to be restored to normal position in time to intercept the stop-pin 84^a, and thus arrest the rotation of the cylinder before the edge 22^a of the inked stencil has reached the face of the platen-roller 30, and it will be impossible for said inked stencil to soil the face of said roller 30, except by abusing the operation of the machine, as by vibrating the stop-arm 84 manually out of the path of the stop-pin 84^a.

It will be noted that the relation of the roller 70 to the cam-plate 71 provides that the series of pressure-rolls 56 be brought into contact with the work-sheet, and any excessive movement of the rod 63 is absorbed by compressing the spring 65 after the rolls 56 have been shifted to a position of rest against the paper, and this excess in motion will compensate for any structural variation in the associated parts without close adjustments, and further allows the rolls 56 to automatically adapt themselves to varying thickness by work-sheets.

At the end of a stenciling period, the key 47 may be depressed to withdraw the latch 45 from the tongue 44 of the lever 42, and permit the lever to respond to the action of the 5 spring 48^a and to the force of gravity of the platen-roller 33 and the feed-rolls 52 suspended from the rod 36, to swing the lever 42 to a raised or normal stop position where the tongue 44 will be arrested by a stop-member 10 89 forming an integral part of the latch 45. The downward stroke of the key 47 is arrested by a stop-pin 90 in the side face of the frame 10. The dropping the platen-roller 33 to a normal inoperative position provides 15 that the roller may be readily removed from the open bearings at the ends of the arms 35 for cleaning purposes, and further provides that an ear 91 on the link 38 will engage with and depress the rod 76 to withdraw the pins 20 77 and actuate the connections to the bell-crank 83 to swing the stop-arm 84 thereof out of the path of the stop-pin 84^a, to permit the cylinder to be rotated in either direction during the adjustment of a new stencil or an inking 25 absorbing fabric to the cylinder.

It will, of course, be understood that ink is applied to the inside perforated face of the cylinder to cover an area predetermined by the area of the stencil; that the platen-roller 30 passes from the end of the work-sheet being stenciled, directly to the clean uninked surface of the fabric stretched around the whole outer face of the cylinder; and that with the preventive features herein set forth, where 35 mechanism controlled by the work-sheet pre-determines the extent of initial rotation of the cylinder prior to the stenciling impress, the operator is relieved of the usual annoyance of reproducing ink-smeared stenciled 40 records.

It will be noted that the handle 23 has a fixed relation to the carrier 24 and to the cam-plate 71, and becomes a driving unit to convey rotary movement to the stenciling cylinder; that the handle 23 is arrested at a normal stop position at the lowest point of its rotation, which is the most efficient point for a manual movement by hand; that the carrier and handle are adjustable around 45 the edge of the cylinder to increase or decrease the distance separating the leading edge of the stencil from the carrier, a distance predetermined by the blank heading of the work-sheet to be stenciled; that the 50 adjustment of the carrier to the cylinder does not change the normal or initial stop position for the carrier and handle; that the operator faces Figure 1 and with the left hand feeds the blank forms one by one to the stop-pins 55 77, while the right hand grasps the handle 23 to rotate the cylinder, and with such a mode of operation it is never necessary for the operator to release the handle 23 during a succession of stenciling operations; and 60 65 that successive stenciling operations become

practically continuous unbroken cylinder rotations with the added advantage of having the inking precautionary factor controlled by the work-sheet.

Variations may be resorted to within the 70 scope of the invention, and portions of the improvements may be used without others.

Having thus described my invention, I claim:

1. A stenciling machine having a sheet-feeding couple including a rotatable stencil-carrying cylinder and an impression-roller always in rolling frictional engagement with the cylinder to feed a work-sheet through a stenciling position, said machine also having, 75 in combination, supplemental cam-closed work-sheet-feeding rolls driven by the impression-roller and operable to advance the work-sheet into the bite of said stencil-cylinder and impression-roller, said stencil-cylinder having timing means for controlling the driving of said supplemental rolls by means of said impression-roller.

2. A stenciling machine having a sheet-feeding couple including a rotatable stencil-carrying cylinder and a platen-roller always in rolling frictional engagement with the cylinder to feed a work-sheet through a stenciling position, and also having, in combination, supplemental cam-closed work-sheet-feeding rolls driven by the platen-roller and operable to advance the work-sheet in unison with the advancing stencil on the cylinder to the stenciling position, said cylinder having 95 an adjustable timing means for controlling the work-sheet-feeding mechanism.

3. A stenciling machine having a sheet-feeding couple including a rotatable stencil-carrying cylinder and a platen-roller always in rolling frictional engagement with the cylinder to feed a work-sheet through a stenciling position, and also having, in combination, supplemental cam-closed work-sheet-feeding rolls driven by the platen-roller and arranged first to become operable to advance 105 the work-sheet to the control of the stenciling elements and then become inoperative as work-sheet-feeding elements, said stencil-cylinder having timing means for controlling the driving and release of the supplemental 110 rolls in feeding the work-sheet to the bite between the cylinder and the platen-roller.

4. In a stenciling machine having a sheet-feeding couple including the combination of a rotatable stencil-carrying cylinder, a 115 platen-roller always in operative frictional engagement with the face of the cylinder to derive a rotary movement therefrom to feed a work-sheet in stenciling, normally inoperative cam-closed work-sheet-feeding elements 120 driven by the platen-roller, and means carried by the cylinder and operable during the initial rotation thereof to render the feeding elements effective to advance the work-sheet to a stenciling position, and then re- 125 130

- lease the work-sheet to the feeding control of the cylinder and roller, said means including timing cams on the cylinder.
5. In a stenciling machine having a sheet-feeding couple including the combination of a rotatable stencil-carrying cylinder, a platen-roller always in operative frictional engagement with the face of the cylinder to derive a rotary movement therefrom to feed a work-sheet in stenciling, work-sheet-feeding means including a feed-roll positively driven by the platen-roller and a pressure-roll therefor normally separated from said feed-roll for the insertion of a work-sheet, and means carried by the cylinder and operable during the initial rotation of the cylinder to close the feeding elements to advance the work-sheet to a stencil-feeding position, said last means including cams adjustable upon the cylinder to time the feeding entrance of the work-sheet and time the stenciling operation to the leading-in edge of the work-sheet.
6. In a stenciling machine having a sheet-feeding couple including the combination of a rotatable stencil-carrying cylinder, a platen-roller always in operative frictional engagement with the face of the cylinder to derive a rotary movement therefrom to feed a work-sheet in stenciling, work-sheet-feeding means including a plurality of feed-rolls geared to the platen-roller to rotate therewith and a series of pressure-rolls therefor normally separated from the feed-rolls for the insertion of a work-sheet, and means carried by the cylinder and operable during the rotation thereof to effect the vibration of the pressure-rolls into work-sheet-feeding relation with the feed-rolls to advance the work-sheet to a stenciling position, said pressure-roll-vibrating means including timing cams operative to determine the extent of sheet-feeding.
7. In a stenciling machine having a sheet-feeding couple including the combination of a rotatable stencil-carrying cylinder, a platen-roller always in operative frictional engagement with the face of the cylinder to derive a rotary movement therefrom to feed a work-sheet in stenciling, work-sheet-feeding elements driven by the platen-roller, pressure-rolls over said feeding elements, normally open for the insertion of a work-sheet between them, and means carried by the cylinder including a cam that becomes operative through intermediate mechanism to force the pressure-rolls into sheet-feeding engagement to advance the work-sheet to a stenciling position, said cam also determining the pressure-roll-feeding distance for the work-sheet.
8. In a stenciling machine having a sheet-feeding couple, the combination of a rotatable stencil-carrying cylinder mounted on a frame and having a free initial rotary movement between stops in advance of a stenciling position determined by a platen-roller always in operative frictional engagement with the face of the cylinder, and mechanism rotated with the cylinder and co-operative with means on the frame controlled by a work-sheet to ensure a full rotation of the cylinder in a stenciling direction.
9. In a stenciling machine, the combination of a rotatable stencil-carrying cylinder having a free initial rotary movement in advance of a stenciling position, a platen-roller always in operative engagement with the face of the cylinder to determine the stenciling position, a camming element rotatable with the cylinder, and cam-actuated mechanism operable during the free movement of the cylinder, to arrest or release the cylinder adjacent the stenciling position according to a predetermined plan.
10. In a stenciling machine, the combination of a rotatable stencil-carrying cylinder having a free initial rotary movement in advance of a stenciling position, a platen-roller always in operative engagement with the face of the cylinder to determine the stenciling position, a stop to arrest the rotation of the cylinder in a stenciling direction and in advance of the stenciling position, and means rotated with the cylinder and co-operative with mechanism on the frame to render the stop either operative or inoperative during the free movement of the cylinder according to a predetermined plan.
11. In a stenciling machine including a stenciling cylinder having a free rotary movement between a normal stop position and a stencil-preventing stop position, the combination of feeding means to advance a work-sheet to be stenciled, and mechanism controlled by the work-sheet and operatively connected to the stencil-preventing stop to release the cylinder for a full stenciling rotation.
12. In a stenciling machine including a stenciling cylinder having a free rotary movement between a normal stop position and a stencil-preventing stop position, the combination of feeding means to advance a work-sheet to be stenciled, and leading-in stop-pins that first gage the work-sheet to the feeding means and subsequently become operative to condition the stencil-preventing stop to promote a full stenciling rotation of the cylinder.
13. In a stenciling machine including a stenciling cylinder having a free rotary movement between a normal stop position and a stencil-preventing stop position, the combination of feeding means to advance a work-sheet to be stenciled, and leading-in stop-pins that are operative to first gage the work-sheet to the feeding means and subsequently are controlled by the feeding work-sheet to render the stop inoperative to prevent a stenciling rotation of the cylinder.
14. In a stenciling machine including a stenciling cylinder having a free rotary move-

- ment between a normal stop position and a stencil-preventing stop position, the combination of feeding means to advance a work-sheet to be stenciled, leading-in stop-pins that are operative to gage the work-sheet to the feeding means, and mechanism actuated by the rotating cylinder that operates to withdraw the pins to release the work-sheet to the feeding means, said pins being subsequently released to the control of the work-sheet to determine the extent of rotation of the cylinder.
15. In a stenciling machine including a stenciling cylinder having a free rotary movement between a normal stop position and a stencil-preventing stop position, the combination of feeding means to advance a work-sheet to be stenciled, leading-in stop-pins that are operative to gage the work-sheet to the feeding means, a cam rotatable with the cylinder, and mechanism actuated by the rotation of the cam that operates to withdraw the pins to release the work-sheet to the feeding means, said pins being subsequently released to the control of the work-sheet to determine the extent of rotation of the cylinder.
16. In a stenciling machine including a stenciling cylinder having a free rotary movement between a normal stop position and a stencil-preventing stop position, the combination of feeding means to advance a work-sheet to be stenciled, leading-in stop-pins that are operative to gage the work-sheet to the feeding means, and a cam rotatable with the cylinder and operable to render the work-sheet-feeding means effective, simultaneously withdraw the pins from the path of the sheet, and subsequently release the pins to the control of the work-sheet to promote a full rotation of the cylinder.
17. In a stenciling machine including a stenciling cylinder having a free rotary movement between a normal stop position and a stencil-preventing stop position, the combination of feeding means to advance a work-sheet to be stenciled, leading-in stop-pins that are operative to gage the work-sheet to the feeding means, and a cam rotatable with the cylinder and operable to render the work-sheet-feeding means effective and withdraw the pins from the path of the sheet, said cam including a dwell face operative during the continuous rotation of the cylinder to time the subsequent release of the pins to the control of the feeding work-sheet and render the stop ineffective to arrest the rotation of the cylinder.
18. In a stenciling machine including a rotatable stencil-carrying cylinder, the combination of a platen-roller always in frictional engagement with the cylinder and conditioned to feed a work-sheet through a stenciling position, a supplemental feed-roll conditioned to be positively rotated by the cylinder-rotated platen-roller, and a normally-inoperative pressure roll having connections

that are rendered operative by the rotation of means on the cylinder to bring the roll into co-operation with the rotating supplemental feed-roll to advance the work-sheet to the stenciling position.

19. In a stenciling machine including a rotatable stencil-carrying cylinder, the combination of a platen-roller always in frictional engagement with the cylinder and conditioned to feed a work-sheet through a stenciling position, a supplemental feed-roll conditioned to be positively rotated by the cylinder-rotated platen-roller, and a normally-inoperative pressure roll having connections that are rendered operative by the rotation of means on the cylinder to bring the roll into co-operation with the rotating supplemental feed-roll to first advance the work-sheet to the stenciling position and then become inoperative to feed after the cylinder and platen-roller have become work sheet-feeding elements.

20. In a stenciling machine including a rotatable stencil-carrying cylinder, the combination of a platen-roller always in frictional engagement with the cylinder and conditioned to feed a work-sheet through a stenciling position, a supplemental feed-roll conditioned to be positively rotated by the cylinder-rotated platen-roller, a normally-inoperative pressure roll operable to co-operate with the supplemental feed-roll to feed the work-sheet to the stenciling position, and a camming element rotated with the cylinder and operative through intermediate connections to the pressure roll to effect the feed of the work-sheet for a predetermined interval.

21. In a stenciling machine including a rotatable cylinder and an inked stencil thereon to be rotated therewith from a normal position to a stenciling position, the combination of a platen-roller always in engagement with the cylinder to determine the stenciling position, work-sheet-feeding means to advance a sheet to the stenciling position to receive a stencil impression, and mechanism controlled by the work-sheet to prevent the stencil from subsequently re-entering the stenciling position after the completion of the stenciled work-sheet.

22. In a stenciling machine including a rotatable stencil-carrying cylinder, the combination of a platen-roller always in engagement with the cylinder and conditioned to feed a work-sheet through a stenciling position, and a pair of supplemental work-sheet-feeding rolls, one roll always rotatable with the platen-roller and the other roll conditioned to be pressed into work-sheet-feeding engagement with the first-named roll during the initial rotating movement of the cylinder, to advance the work-sheet and effect a joint entrance of the work-sheet and a stencil to the stenciling position, and to the platen-roller-feeding control.

23. In a stenciling machine including a rotatable stencil-carrying cylinder, the combination of a platen-roller always in work-sheet-feeding engagement with the cylinder, a series of feed-rolls rotated by the platen-roller, a series of normally-inoperative pressure rolls that may be rendered operative to co-operate with the feed-rolls to feed a work-sheet to the feeding control of the platen-roller, a camming element rotated with the cylinder, and mechanism on the frame that is operable by the cam, including a resilient connection to operate the pressure rolls and compensate for varying thicknesses of work-sheets.
24. In a stenciling machine including a rotatable cylinder, the combination of a shiftable frame underlying the cylinder, work-sheet-feeding means carried by the frame, including a platen-roller to engage the surface of the cylinder and a series of feed-rolls rotated by the platen-roller, a shift-key operable through mechanism connected to the frame to raise the platen-roller and feed-rolls into operative relation to the cylinder, and a latch to engage the key and hold the frame in its raised position during a continuous stenciling interval.
25. In a stenciling machine including a rotatable cylinder, the combination of a shiftable frame underlying the cylinder, work-sheet-feeding means carried by the frame including a platen-roller to engage the surface of the cylinder and a series of feed-rolls rotated by the platen-roller, a shift-key operable through mechanism connected to the frame to raise the platen-roller and feed-rolls into operative relation to the cylinder, and a latch operative at one position thereof to lock the depressed key and hold the frame in a raised operative position and at another position to arrest the released key and assume the weight of the frame when the latter is shifted out of operative relation to the cylinder.
26. In a stenciling machine including a rotatable stencil-carrying cylinder, the combination of a platen-roller always in work-sheet-feeding engagement with the cylinder, a series of feed-rolls rotated by the platen-roller, a series of pressure rolls operative to be pressed into engagement with the feed-rolls for a joint work-sheet-feeding movement, a series of leading-in stop-pins between the feed-rolls and the platen-roller to gage the work-sheet relatively to the feed-rolls, a camming element rotatable with the cylinder, and mechanism actuated by the camming element, while being rotated by the cylinder, to withdraw the leading-in pins, and render the pressure rolls operative to effect the feeding of the work-sheet to the control of the platen-roller.
27. In a stenciling machine including a cylinder rotatable between a normal stop and a stenciling-prevention stop operable to arrest the cylinder in advance of a stenciling position, the combination of a platen-roller that is in frictional engagement with the surface of the cylinder and determines the stenciling position of the cylinder, work-sheet-feeding mechanism operable by the rotating cylinder to carry a work-sheet to the stenciling position of the platen-roller, and mechanism controlled by the feeding-in of the work-sheet that is operable to remove the stenciling-prevention stop from the path of the rotating cylinder.
28. A stenciling machine including a rotatable stenciling cylinder, a work-sheet-support co-operating with said cylinder to advance a work-sheet past the stenciling position, work-sheet feeding means in advance of said support, work-sheet-stops arranged between said support and said feeding means, means for rendering said stops inoperative, and means for throwing said feeding means out of operation while said stops are in their inoperative position.
29. A stenciling machine including a rotatable stenciling cylinder, a work-sheet-support co-operating therewith to advance a sheet past the stenciling position, a feed-roller in advance of said support, a pressure-roller mounted on a rocker-arm so as to be capable of movement toward and away from said feed-roller, a cam on said cylinder, a second rocker-arm controlled by said cam, and a resilient connection between said rocker-arms to permit the pressure-roller to press yieldingly against said feed-roller to feed work-sheets of different thicknesses to said cylinder upon actuation of said second-mentioned rocker-arm by said cam.
30. A stenciling machine including a rotatable stenciling cylinder, a work-sheet-support co-operating therewith to advance a work-sheet past the stenciling position, intermittently operated work-sheet feeding means in advance of said support, a handle-member on said cylinder and circumferentially adjustable thereon so as to predetermine the extent of the blank space at the top of the work-sheet, and a timing cam adjustable as a unit with said handle-member and operable through intermediate mechanism to control said feeding means.
31. A stenciling machine including a rotatable stenciling cylinder, a platen-roller co-operating with said cylinder to advance a work-sheet past the stenciling position, a normally continuously operative stop for automatically limiting further movement of said cylinder in a stenciling direction after the completion of a stenciling cycle, and means for throwing said stop out of operation.
32. A stenciling machine including a rotatable stenciling cylinder, a platen-roller co-operating with said cylinder to advance a

work-sheet past the stenciling position, a stop for limiting further movement of said cylinder in a stenciling direction after the completion of a stenciling cycle, and work-sheet-controlled means for rendering said stop inoperative when a sheet is in proper position in front of the platen-roller.

33. A stenciling machine including a rotatable stenciling cylinder, a platen-roller co-operating therewith to advance a work-sheet past the stenciling position, a feed-roller in advance of said platen-roller, a pressure-roller overlying said feed-roller and rockably mounted so as to be capable of swinging into and out of engagement with said feed-roller, a stop normally operative to engage a fixed member on said cylinder to limit the rotation of the latter in a stenciling direction, a timing cam on said cylinder, and means controlled by said cam for swinging said pressure-roller into engagement with said feed-roller and rendering said stop inoperative.

34. A stenciling machine including a rotatable stenciling cylinder, a platen-roller co-operating therewith to advance a work-sheet past the stenciling position, movable stops in front of said platen and against which a work-sheet may be aligned, a stop normally operative to engage a fixed member on said cylinder to limit the rotation of the latter in a stenciling direction, a cam on said cylinder, a rock-shaft disposed below said cylinder, crank-arms fixed on said shaft and pivotally connected, respectively, to said first and said second mentioned stops, and means controlled by said cam for rocking said shaft to move all of said stops out of operative position.

35. In a stenciling machine having a stenciling cylinder and a platen-roller co-operating therewith, the combination of a rock-shaft disposed below said roller, movable stop-pins projecting above a paper-feed table in front of said roller, and a movable cylinder-stop normally in the path of a fixed element on said cylinder to limit the movement of said cylinder in a stenciling direction, said stop-pins and said stop being connected to said rock-shaft, the movements of the parts connected to said shaft with respect to the shaft being so counterbalanced that in the absence of a work-sheet on said table, said pins will project above said table and said shaft will rock so as to cause movement of said cylinder-stop to operative position, but the pressure on said pins of a work-sheet being fed to the cylinder and platen-roller will be sufficient to cause depression of the pins and rocking of said shaft in an opposite direction to cause movement of said cylinder-stop to inoperative position.

LINDEN A. THATCHER.
